UNITED STATES PATENT OFFICE.

GUY L. CAMPBELL AND BERKLEY KING POSTLETHWAITE, OF MINNEAPOLIS,
MINNESOTA.

TRACTION-ENGINE.

1,058,546.

Specification of Letters Patent.

Patented Apr. 8, 1913.

Application filed February 16, 1911. Serial No. 608,954.

To all whom it may concern:

Be it known that we, GUY L. CAMPBELL and BERKLEY K. POSTLETHWAITE, citizens of the United States, and residents of Minneapolis, in the county of Hennepin and State of Minnesota, have invented a new and Improved Traction-Engine, of which the following is a full, clear, and exact description.

Among the principal objects which the present invention has in view are: To provide an engine of the character described, having a plurality of carrying wheels and a belt-like bed for increasing the ground surface contact; to provide an engine of the character mentioned with means for augmenting the traction pull of the driving wheels and with hauling devices of suitable construction and arrangement; and to provide a frame and supporting wheels therefor arranged to flexibly accommodate the wheels to the road bed, and to dispose the hauling strain directly upon the axles of the traction wheels.

One embodiment of the present invention is disclosed in the structure illustrated in the accompanying drawings, in which like characters of reference denote corresponding parts in all the views, and in which—

Figure 1 is a side elevation of an engine constructed and arranged in accordance with the present invention; Fig. 2 is a top plan view of the same, the superstructure being removed and one set of driving wheels being shown in section, the section being taken on the line 2—2 in Fig. 3; Fig. 3 is a front end elevation of a traction engine constructed and arranged in accordance with the present invention; Fig. 4 is a detail view in rear elevation, showing the arrangement of the engine, chassis frame and traction mechanism; Fig. 5 is a detail view, on an enlarged scale and in side elevation, showing the side framing beams of the chassis and in conjunction therewith the carrying axles and draw bar; Fig. 6 is a detail view in horizontal section, taken on the line 6—6 in Fig. 5; Fig. 7 is a detail view in perspective of a bearing box for the carrying axles; and Fig. 8 is a detail view on an enlarged scale,

showing a fragment of a carrying axle and a bearing box therefor, the bearing box being shown in vertical section.

A tractor constructed and arranged in accordance with the present invention comprises a plurality of mechanical elements, which may be best grouped in their more intimate or interdependent relation. The groups referred to may be generalized under the headings as follows:—The traction mechanism, comprising the means for carrying and propelling the engine, and the transmission mechanism necessary to connect the traction mechanism with the prime mover:—The cable traction mechanism, comprising the means for propelling the engine, using in conjunction therewith an anchored cable:—The driving mechanism:—The steering mechanism:—and, The hauling devices.

The traction mechanism.—As shown in the accompanying drawings, the traction mechanism is provided with the endless belt bed, the plate links 15, 15 whereof are, as shown, rectangular in form and each provided with a central opening 16 for the reception of sprocket projections 17. The projections 17 are extended from the felly of the wheels 18, 18. The wheels 18, 18 are disposed in paired arrangement and are rotatively mounted on the rounded ends 19 of the squared axles 20. The axles 20 are separated, as shown in the drawings, and are mounted in boxes 21, the flanges 22, 22 whereof straddle a bolster frame 23 in guided relation thereto. The boxes 21, 21 are constructed to a shorter dimension than the length of the openings 24, 24 in the ends of the bolster frame 23, and larger than the opening 25 formed at the center of the said bolster. The purpose of the arrangement is that by adjusting the plates 26, 26 to the outside or inside of the boxes 21 the axles 20, 20 may be disposed in closer or more separated relation.

The bolster 23 is rigidly bolted to side bars 27 of the chassis or frame of the tractor. The bolster is provided with spring cups 28, 28 arranged to receive in holding relation the springs 29, 29. The springs 29 rest upon equalizing bars 30, 30. The bars

30, 30 are shaped as best shown in Fig. 5 of the drawings, and rest upon and over the axles 20, 20 and the center axle 31. The purpose of the construction thus described 5 is to balance, equalize and distribute the carrying strain upon and between the wheels 18, 18 and 32.

The wheel 32 is rotatively mounted on the axle 31, and is provided with separated 10 sides 33, 33. The sides 33, 33 are integrally connected with the hub of the wheel 32, and form a space for the reception of the wheels 18, 18, as shown best in Fig. 2 of the drawings. The diameter of the 15 wheels 18, 18 and 32 is the same, therefore the tread of the three wheels, under normal conditions, is on the same level. The tread of the said wheels is upon the inner surface of the plate links 15, 15. It will be understood 20 that the wheel 32 has no rigid connection with the plate links 15 or the traction bed formed thereby.

By reason of the arrangement of the carrying wheels as described the bearing 25 of the wheels on the ground is amplified and the bearing points more nearly drawn together.

Each of the wheels 18, 18 is provided with a sprocket wheel 34. The sprocket wheels 34 are fixedly mounted on the hubs of the wheels 18, and are operatively connected by means of a chain 35. The chain 35 is extended between the said wheels 34 in engagement with the teeth thereof, and is 35 passed under a sprocket wheel 36 which is fixedly mounted on a driving shaft 37. In its engagement with the sprocket wheel 36 the chain is held by an idler sprocket wheel 38 which is mounted on a shaft 39 40 between the members of a yoke 40. The yoke 40 is pivoted on a shaft 41, and is directly connected with a pull spring 42 attached to the tail end 43 of the said yoke 40. This construction provides a yielding 45 slack absorber for the chain 35.

The driving shaft 37 is made in two pieces, centrally united by means of a differential gearing. The differential gearing is of usual construction, differing only in that for 50 the usual gear teeth of the driving member thereof is substituted a worm gear wheel 44. Meshed with the teeth of the worm gear wheel 44 is a worm 45 which is fixedly mounted on the driving shaft 46 of the traction mechanism. The driving shaft 46 is engaged with the driving shaft of the driving mechanism by means of a clutch 47.

The operation of the traction mechanism when the shaft 37 is rotated is as follows: 60 By means of the chain 35 the wheels 18 are rotated on the axles 20, 20. The wheels 18 engaging the plate links 15 move over the same, forming thereby a carrying bed for the engine. As the ground over which the

engine is moving is irregular in surface, 65 the bed formed by the plate links 15 is raised in contact with the central wheel 32, rotating the same and being held thereby in rigid contact with the ground. By means of the spring carriage heretofore described the 70 central wheel is moved outward to bear against the ground under all conditions, and to equalize the carrying strain on the three wheels on each side of the engine. The shaft 37 is rotated in the direction needed to 75 drive the chain 35 to rotate the wheels in a forwardly tracking direction. The shaft being held in the bracket bearings 48, and these being rigidly bolted to the frame of the engine, the pulling strain of the chain 80 35 on the wheels 34, 34 is positive. By reason of the construction and mounting of the wheels 38, as shown in the drawings, any slack in the chain 35 will be taken up by the yoke 40 rocking on the shaft 41. By 85 reason of the differential gear connection of the parts of the shaft 37 the speed of the wheels on each side of the engine is accommodated to any curvature in the path of the said engine. 90

The cable traction mechanism.—When, as sometimes occurs, the necessary propulsion for the traction engine is not obtained by the traction mechanism, as, for instance, when operating over ground provided with 95 a heavy undergrowth or where the ground is soggy or slippery, the propulsion is assisted by means of a mechanism for winding an anchored cable. When employing this method of propelling the engine the 100 drums 49 and 50 are employed. The drums 49 and 50 are constructed of different diameters, and are each fixedly mounted on different portions of the driving shaft 37. Under all conditions of this character 105 a cable is carried forward to a point of anchorage and there secured. The free end of the cable is wound on one or other or both of the said drums as follows:—The drum 49 is preferably formed to a diameter 110 which will cause to be wound upon the said drum a portion of the cable equal to the traction propulsion of the engine, whereby the propelling effect of the traction mechanism and the cable traction mechanism is at the 115 same rate, no slippage for the plate links 15 being provided for. Under many conditions this is all the assistance required by the traction mechanism. Where, however, the conditions require a propulsive force in 120 excess of that provided by winding the cable on the drum 49, the cable is wound upon the drum 50, which, being of much less diameter than the drum 49, exerts a greater leverage or pull on the cable. It will be 125 observed in this connection that the traction mechanism aids the pull on the drum 50 to the extent represented by the slipp-

page of the plate links 15, it being understood that the rate of cable winding is slower than the traction drive of the wheels 18.

5 When a yet greater carriage propulsion force is required than that obtained by winding the cable upon the drum 50, this may be obtained by providing a block pulley at the point of anchorage and in reeving the cable through the said block and winding both free ends of the said cable on the two drums 49 and 59 and in opposite directions. These drums operating at different rates of speed, and the cable accommodating itself to the rates of speed, a multiplied force efficiency is acquired at the expense of the rate of speed. When thus rigged the maximum propulsive force is exerted upon the engine.

20 *The driving mechanism.*—The driving mechanism may consist of any approved form of prime mover. That shown in the accompanying drawings, and preferred by us, consists of a multi-cylinder internal combustion engine 51. The engine 51 is suitably mounted upon a bed plate 52, and is provided with balancing fly wheels 53, 53. At each end of the crank shaft of the engine are provided the clutches 47 and 54. The 30 operation and purpose of the clutch 47 is above described; that of the clutch 54 is to operatively connect a short shaft 55 with the said crank shaft. The shaft 55 is provided with a bevel gear wheel 56 fixedly 35 mounted on said shaft and meshed with a bevel gear wheel 57. The gear wheel 57 is fixedly mounted upon a shaft 58 carrying the driving pulley 59. The pulley 59 is used, as a rule, as an auxiliary member, 40 permitting the engine to be utilized as a power plant when the traction mechanism is not employed. The pulley 59 is also, at times, engaged when it is necessary to draw backward the engine, in which action the 45 efficiency of the traction mechanism is not sufficient to start the engine.

The controlling devices or mechanism usual to the handling of engines of the character indicated are not shown in the 50 accompanying drawings. Any suitable devices may be employed.

55 *The steering mechanism.*—The steering mechanism employed for guiding the engine has an elongated tiller post 60. The tiller post 60 is set at an incline, shown best in Fig. 1 of the drawings, and in this position is suitably mounted, and is provided at the forward and lower end with a worm 61. The worm 61 is meshed with a worm wheel 62. The wheel 62 is fixedly mounted on a shaft 63. The shaft 63 has fixedly mounted thereon a winding drum 64 upon which is wound a cable or chain 65. The ends of the chain 65 are connected to eyelets 66

formed on the carrying axle 67 provided for 65 the steering wheels 68, 68.

The axle 67 is connected with the bolster 69 by a ball and socket joint 70. The ball and socket joint 70 thus formed permits the axle 67 and wheels 68 connected therewith 70 to be deflected in the path of travel, and to rock transversely and independently of the frame of the engine. The advantage of such a construction in unbroken or heavy ground is obvious. The chain 65 lends itself 75 freely to this action on the part of the axle 67.

The forward part of the frame of the engine resting on the wheels 68, 68 is provided with a tank 71 and a bonnet 72. Sufficient weight is imparted to the forward end 80 of the frame by this construction to cause the colter flange 73 on each of the said wheels to sink into the ground, thereby preventing side slippage of the said wheels, 85 and increasing the efficiency of the steering gear. In operating the steering gear the tiller post 60 is rotated by means of a hand wheel 74.

90 *The hauling devices.*—The hauling devices shown in the accompanying drawings consist of a spreader bar 75 which is supported upon the ends of draw bars 76, 76. The draw bars 76, as shown best in Fig. 5 of the drawings, are pivotally connected at 77 to the bolsters 23, 23. By means 95 of this connection it will be appreciated that the pulling strain of the engine is initially received upon the axles of the driving wheels and the housing therefor. In this manner 100 the raking strain peculiar to the employment of engines of this character is not transmitted through the framing structure. Thus is a large proportion of the usual wear and tear of the framing structure avoided. 105

The draw bars 76, 76 are supported by means of spiral springs 78, 78, these being disposed in housings 79, 79. By thus supporting the draw bars 76 they are permitted to yield to down pulling strains which otherwise might be exerted upon the frame of the machine to lift the forward end thereof and the steering wheels from the ground. 110

As shown best in Fig. 2 of the drawings, the spreader bar 75 is reinforced and braced 115 by means of tie rods 80, 80 and turn buckles 81, 81 formed on the said tie rods.

Having thus described our invention, what we claim as new and desire to secure by Letters Patent is:—

120 A traction engine, comprising a carrier frame having vertically disposed guide members; a plurality of carrying axles having parallel side sections disposed in said guide members and provided with cylindrical 125 bearing sections extended beyond the frame of the engine; a plurality of traction wheels having sprocket members extended from the

periphery of said wheels rotatably mounted on said axles; a driving mechanism embodying a prime mover and a plurality of chain connected sprocket wheels fixedly mounted on said traction wheels; and a plurality of traction belts extended around said traction wheels provided with recesses to receive the sprockets of said wheels.

In testimony whereof we have signed our names to this specification in the presence 10 of two subscribing witnesses.
